BUILDING CONSTRUCTION AND CLIP
MEANS THEREFORBruno E. Balduf, Chicago, Ill., assignor to United
States Gypsum Company, Chicago, Ill., a cor-
poration of IllinoisApplication October 13, 1933, Serial No. 693,427
In France July 6, 1931.

17 Claims. (Cl. 72—118)

This invention relates to building construction and has to do more particularly with constructions in which there are provided means for connecting various structural parts in spaced relationship, such as in walls, ceilings or floors.

This application is a continuation in part of my co-pending application, Serial No. 543,318, filed June 10, 1931, now matured to Patent No. 1,935,536 and entitled, "Building construction".

- 10 In my said co-pending application there are disclosed various forms of resilient clip connecting means for sound insulated walls, etc., which are adapted for side attachment to a stud or building member. The type of clip connection set forth in the present disclosure, however, is adapted for attachment directly to the face of a building member regardless of its nature and may be used either in sound insulated constructions, or in structures where sound insulation is not 15 particularly essential but it is desirable to provide for substantially spaced relationship between the component parts of the structure, so as to provide for a substantial degree of potential movement between the parts after erection. A spaced relationship is also desirable for other reasons which will become apparent from the following detailed description, or will be found inherent in the structure under various conditions in practice.

- It is an aim of the present invention, therefore, 20 to provide a connecting clip which may be readily secured to the face of a structural member and will form a substantial connector for another structural member in spaced relationship to the first member.

- Another object of the invention is to provide 25 means whereby a building member designed to form all or a part of the finished surface of the structure can be attached in spaced relationship to a variety of base members, such as building

- 40 tile, masonry, brick, wood, etc. Another object of the invention is to provide a construction in which a massive or basic structural member and an overlying structural member of lighter construction are connected in 45 spaced relationship in a manner to permit some relative movement of the massive or basic structure without damaging the overlying structure.

- Another object of the invention is to provide a 50 clip for building construction which can be nailed or otherwise secured to the face of one building member and slidably engage another building member in spaced relationship to the first member.

- Another object is to provide a method of building construction in which there is a supporting

member of somewhat variant or uneven face surface and a building element connected thereto which, however, is to be maintained with a substantially uniform face plane, wherein clips having bendable portions are used as the connecting means and permit compensating for the variations or unevennesses in said supporting member by bending the clips as necessary to bridge the various spacings between the said member and element.

Another object is to provide a building construction and clip means therefor which is economical, simple to erect and efficient in use; also to improve building structures and clip means therefor in other respects hereinafter specified 15 and claimed.

Reference is to be had to the accompanying drawings, forming a part of this specification, in which:

Fig. 1 is a sectional perspective view showing a 20 preferred form of clip in use in a building construction;

Fig. 2 is a similar view showing a modified form of clip;

Fig. 3 is a fragmentary elevation showing either 25 of the clips of Figs. 1 and 2 in place against a brick wall;

Fig. 4 is similar to Fig. 3 and shows the use of metal lath in the construction;

Fig. 5 is a fragmentary perspective view of a 30 wall construction in which there is employed a modified form of clip;

Fig. 6 is a fragmentary perspective view of a 35 floor construction in which clips of the type herein contemplated are employed;

Figs. 7 and 8 are fragmentary perspective views of constructions in which the clips are provided with means for direct engagement of building panels;

Figs. 9 and 10 are perspective views of modified 40 forms of clips;

Fig. 11 is a perspective view of a modified form of clip adapted for supporting metal lath; and

Fig. 12 is an elevation of a form of clip for use 45 at the corner of a room.

In the construction of a building, the base member for walls, floors or ceilings may comprise any of a number of materials, such as wood, gypsum partition or floor tile, brick, concrete, etc. In order to hide the rough base structure 50 and provide a wearing surface or decoration base, there is generally applied thereover a structure of lighter construction which may comprise wallboard, plasterboard and plaster, metal lath and plaster, etc., in the case of walls and cell- 55

ings; and finish flooring in the case of floors. It is often necessary or desirable to substantially space apart this finishing surface from the framework or other massive or basic member of the building in order to take care of any one or more of a number of different conditions such as for sound insulation, thermal insulation, to permit movement of one building member relative to another after erection, to permit erecting a finishing surface having a substantially uniform face plane regardless of unevennesses or variations in the supporting structure, to prevent moisture which may seep through the base structure from attacking the finish surface, or the like. The present invention provides for constructions of this nature.

In Fig. 1 there is shown a building member 15 on the face of which are secured clips 16 which engage and support a metallic channel strip or runner 17 in spaced relationship to member 15. Each of clips 16 is provided with a resilient loop 18 having a laterally extending U-shaped flange 19 adapted to form a base to rest against the face of member 15 for attachment thereto, said flange 19 being preferably suitably apertured to receive nails 20 or other attaching means for securing the clips to member 15. The opposite end of loop 18 is provided with a flange 22 which is reverse bent to form a U-shaped flange or seat 23 adapted to receive a flange 24 of channel strip 17 for the purpose of supporting the channel in position. A flange 25 is formed on seat 23 to engage the web of channel 17 and prevent displacement of the channel from the seat. Clips 16 may be placed in engagement with channel strip 17 by a simple manipulation of the same to snap onto flange 24 of the channel; or, where desired, flange 25 may be initially formed as a straight extension of seat 23, and after the channel flange 24 has been placed into position in seat 23, flange 25 may be bent over upon the web of channel 17. The apertured portion of flange 19 is preferably extended laterally a sufficient distance beyond loop 18 to permit free perpendicular access for the purpose of driving or otherwise placing attachment means 20. If the member 15 should be a metallic beam, girder, or the like, flange 19 may be formed to engage a flange of said beam as described in my aforementioned co-pending application. It will be apparent that by providing a simple clip which may be readily secured to any portion of the face of a structural member in any desired position, a very valuable feature has been contributed by the present invention. Erection is facilitated and the erector is permitted greater freedom of design and manipulation than in constructions heretofore employed.

Where sound insulation is not an important desideratum in the construction, but it is desired to space the structural members apart and maintain some flexibility in the construction, a furring clip, such as shown in Fig. 2, may be used. In this form of clip there is provided a substantially straight body portion or leg 27, of preferably, though not necessarily, considerable length relative to other portions of the clip, said body portion being provided with flange 28 at an angle thereto and adapted to form a base for attachment against the face of a building member 15 by nails or other attachment means 29. The opposite end of body portion 27 is provided with an arrangement similar to that described for clip 16 and application of the clip to a channel

strip 17 is similarly performed. The body portion or leg 27 of the clips is preferably arranged to extend at an angle relative to the surface of member 15 to which the clips are attached, this angle being such that when the clips are in place the clip legs will diverge to the sides of channel 17 and ready access may be had to drive nails 29 through flanges 28. When in place, therefore, the legs 27 will be in opposed angular relation to one another and provide considerable lateral stability to the channel 17 supported thereby. The body portion 27 is also preferably bendably connected to the other parts of the clips or made of comparatively soft metal, which, while permitting the clips to be bent when necessary, is yet not of such softness as to impair the efficiency of the clips in use. Thus, the relative position of members 23 and flanges 28 of the clips is readily variable by a simple bending operation, whereby to accommodate variations in the spacing between the members being connected. With this feature it is possible, for example, to place channel 17 with a substantially uniform face plane regardless of variations such as disalignment, warping, etc., or unevennesses in member 15 or other base member adjacent which channel 17 may be supported. This relative bendability is also of advantage when, in the finished construction, relative structural movement or warping takes place in the supporting structure whereupon the clips will give sufficiently to prevent transmission of the movement to the supported structure.

In Figs. 3 and 4 is shown a brick wall 31 to which there is connected in spaced relationship a furring channel strip 17 by means of clips 32. These clips 32 may be of either of the forms shown in Figs. 1 and 2, and are preferably attached to the wall 31 by means of nails 33 driven into the mortar joints between the bricks. It will be noted that clips 32 are shown as placed in staggered relationship along the edges of channel strip 17. In this manner of placement stability can be secured in the strip 17 while using a minimum number of clips. Where desired, however, the clips may be placed opposite one another as seen in Figs. 1 and 2.

Where the finished surface of the building is to comprise plasterboard 34 over which is applied a plastic coating, such as plaster 35, plastic paint, or the like, attaching clips 36 are provided. Oppositely extending fingers 37 are formed on the clips 36, said clips being connected to the channel strips 17 by a suitable attaching flange 37a and being adapted to engage the edges of the plasterboard 34 to support it. However, where it is desired to provide a plastered wall in which metal lath forms the plaster base, metal lath 38 may be secured to furring channels 17 by means of wires 39 or the like. In either case, a light weight panel structure secured to the channel or runner members 17 is obtained, and where spring loop clips 16 are used in the structure, the shock of impinging sound waves or other concussions against the light weight panels or the heavier structural members will be absorbed by the clips and thus substantially prevented from transmission through the construction.

The modified form of furring clip shown in Fig. 5 comprises a substantially straight body part 40 provided at one end with a flange 41 adapted to rest against and to be secured to the building surface 42 by means of nails 43 or the like. A plate 44 is secured, as by spot-welds 45, to flange 46 formed on the opposite end of body portion 40

of the clip, and is provided with a plurality of laterally extending fingers 48 adapted to bear against the web of furring runner 17. A U-shaped flange 49 is adapted to engage a flange 24 of channel 17. Provision is preferably made for receiving a plurality of nails or other attachment members 43 for securing the clips against the structural member 42 so that the clips will be substantially prevented from pivoting due to pressure brought against strip 17. The building member 42 may comprise any type of material employed for the purpose such as partition tile, wood, brick, etc., since from the nature of the furring clips employed, they may be readily attached to the face of the member regardless of its nature.

In a floor construction, there may be employed clips 50 having a spring loop body portion 51 provided with a return bent flange 52. Apertures 20 are preferably formed in flange 52 to receive a nail or other suitable attaching means 53 so as to secure the clips against the face of a sub-floor 54 which may comprise gypsum floor tile or other suitable material. The flange 52 is preferably 25 made long enough to extend substantially beyond the resilient loop 51, so as to permit substantially free vertical access for driving nails 53 or the like. The opposite end of loop 51 is provided with a return bent L-shaped flange 55 adapted 30 to form a seat for a sleeper 56. A nail or screw 57 is driven through an aperture in flange 55 into the side of sleeper 56 for securing clip 50 thereto. A plurality of clips 50 are used for each sleeper and are preferably secured to alternate 35 opposite sides of the sleeper in spaced relationship. This construction provides an inexpensive resilient structure which is readily adaptable to various conditions.

Where it is desired to provide a plasterboard construction of an even more inexpensive character than that illustrated in Fig. 5, clips such as shown in Figs. 7-10 may be used. In Fig. 7 there is shown a clip 58, comprising a spring loop 59 which is provided at one end with a return bent flange 60 adapted to rest against the face of structural member 61 for attachment thereto. A panelboard-engaging clip 62 is provided with oppositely extending fingers 63, which form channels for receiving the edges of wallboard 64, and 50 is secured to the opposite end of loop 59 by spot welding. In order to permit ready access to secure these clips against the building member 61, even when the flange 60 is partially obstructed by a plasterboard 64, an extension 65 is preferably 55 formed on each side of flange 60. These extensions 65 may be apertured to receive nails or the like 66 for securing the same against member 61. Where furring without substantial sound insulation is desired, the form of clip shown in Fig. 8 60 may be employed. In this form of clip body portion 67 is substantially straight and is provided at one end with a flange 68. An elongated plate 69 is secured as by spot welding to flange 68 in such manner that the ends of the plate extend transversely of the flange, and at least one end will be 65 accessible for the purpose of driving a nail or similar securing means 70 through the plate, whereby to fasten the clip to a structural member 72. The opposite end of body portion or leg 67 70 is provided with a flange 78 secured, as by spot-welding, to a panelboard-engaging clip 74. Where desired, the flange 68 may be provided with extensions similar to extensions 65 formed on flange 60 of clip 58 instead of being combined 75 with attaching plate 69. Likewise, if desired,

flange 60 may be secured to an attaching plate 69 instead of being provided with extensions 65. Body portion 67 may also be of relatively bendable material or be bendably connected to flanges 68 and 73 so that the clips may be arranged to conform to possible variations in the spacing between member 72 and panelboards 75 which are preferably erected in a substantially uniform plane.

The clips shown in Figs. 9 and 10 are modifications and in some respects simplified forms. 10 Clip 76 comprises a resilient loop 77 having one end formed into base flange 78 and the other end provided with a flange 79 to which is secured a panelboard-engaging clip portion 80. Flange 78 is preferably of such a length that its end will 15 extend substantially beyond the end of the panel engaging portion 80, and an aperture 82 is formed therein for the purpose of receiving a nail or other suitable fastening means for attaching the clip to a structural member. In order to permit easy 20 securing of clip 76 to a structural member when flange 78 is obstructed by a panelboard, there is preferably formed along one edge of flange 78 a lateral extension 84 provided with a suitable aperture 85. Instead of having the loop portion 25 of the clip facing longitudinally of the clip portion 80, the clip may take the form shown in Fig. 10, wherein a flange 87 formed on one end of loop 86 is secured transversely of the panelboard-engaging member 80. Thus, base flange 89 which 30 extends substantially beyond fingers 80, is readily accessible for perpendicularly driving a nail or other securing means through flange 89 in which there is preferably formed an aperture 91 for insertion of the securing means. 35

For the purpose of securing metal lath in place in a wall or ceiling construction, clip 93 may be employed to advantage. This clip comprises a resilient loop 94 provided at one end with a reverse bent flange 95 serving as the base for securing 40 the clip against a structural member, and preferably having an aperture 96 through which a nail or the like may be driven in securing the same against the structural member. The opposite end of loop 94 is provided with a flange 97 to 45 which is secured, as by spot-welding, or the like, a plate 98 having struck up therefrom a bendable lug 99. In a building construction, a plurality of clips 93 are secured in place and metal lath is then positioned against plate 98, lugs 99 50 then being bent over to engage the strands of the metal lath. Where sound insulation is not of primary importance, but the advantages of furring the metal lath away from the structural member adjacent which the lath is to be secured 55 are desired, a clip may be provided in the form indicated in dot and dash lines in Fig. 11. There is provided a substantially straight body portion or leg 101 having a base flange 102 at one end, and flange 103 attached to the plate 98 at the other 60 end. Body portion or leg 101 may be of bendable nature in a similar manner and for the same purposes as described in connection with the form of clip in Fig. 2 which has straight legs 20. 65

In order to provide for securing in place building panels at the corner of a room, there may be provided a clip 104 having a loop portion 105, which has a flange 106 formed at one end and secured to a panelboard edge-engaging channel member 107. In order to engage the edge of a 70 panel board converging with the panelboard engaged by member 107, a similar engaging member 108 is secured to the side of member 107. A somewhat off-set flange 110 is provided on the other end of loop 105 and is of sufficient length 75

to extend substantially beyond the edge of member 108 so as to permit driving nails or the like 111 therethrough for the purpose of securing the same against building member 113. A crimp 5 114 may be formed in flange 110 so that the flange may be bent to embrace a corner of plate 115 as shown in broken lines in Fig. 12. When desired, the clip may be provided with a substantially straight shank 117 having a flange 118 secured 10 to the base 119 of board edge-receiving member 107.

While the clip means herein have been illustrated as taking a variety of possible forms to meet various conditions, it will be apparent that 15 the underlying principle of the invention remains the same throughout. The invention provides clips which may be readily secured in any desired operative position on the face of the basic and generally more massive structural elements 20 of a building construction, and more or less resiliently spaces the generally comparatively lightweight finishing structure of the construction substantially away from the underlying supporting structure. Building constructions are subject to structural movements from time to time, such as result from settling of the building, or 25 from contraction or expansion, or the like, and by spacing the structural members apart by means of clips, as herein described, movement taking place in one of the members will be substantially prevented from transmission to the other member because of the inherent resiliency of the clip connection. Where the clips are provided with a resilient loop, a large degree of sound 30 insulation is provided because in each instance these resilient loops are preferably made of a sufficient stiffness so as not to vibrate due to sound waves or concussions impinging against one of the members connected by the clips, but 35 are yet of sufficient flexibility to be initially flexed by impinging waves or concussions, such as will cause a sound audible to the human ear, whereby the impact will be prevented from transmission to the opposite structural member. In a masonry or 40 brick wall facing the exterior of a building, the mortar joints may be defective in spots and therefore allow moisture to be driven therethrough into the interior of the building, but where the finished surface is furred away from 45 the brick or masonry wall, the surfacing member of the construction will be saved from damage because the moisture will be prevented from reaching it. The present invention also provides means whereby in a construction of the class described even though the supporting structure 50 may be of uneven or variant character and it is desired to provide the finishing surface structure with a substantially uniform planar face, the variations in spacing between the structures will 55 not prevent attainment of the objective nor reduce the strength and durability of the construction. Clips are provided which are readily adjustable to suit the variable spacings, and thus substantially obviate the heretofore necessary 60 expedient of building up or furring out under the clips.

I would state in conclusion that while the illustrated examples constitute practical embodiments of my invention, I do not wish to limit myself precisely to these details, as manifestly the same may be considerably varied without departing from the spirit of the invention as defined in the appended claims.

Having thus described my invention, I claim 70 75 as new and desire to secure by Letters Patent:

1. In a building construction, a building frame, a flat metallic spring loop having a U-shaped flange formed on one end, means for attaching said flange to said frame, a second U-shaped flange formed on the opposite end of said spring loop, 5 a runner engaged by said second U-shaped flange, and a lightweight panel secured to said runner and spaced apart from said building frame by said resilient loop.

2. In a building construction, a building panel 10 of massive construction, a pair of resilient spring loops secured to said panel and being oppositely disposed, a channel shaped runner arranged adjacent the opposite end of said spring loops, U-shaped brackets formed on the outstanding ends 15 of said loops and arranged to engage the opposite sides of said channel strip, and a lightweight panel secured to said channel strip and arranged to receive impinging sound waves to be absorbed by the spring loops. 20

3. In a building construction, a building member, a metallic clip secured by nailing to the face only of said member, a surface structure spaced away from said member and connected thereto by said clip, said clip having only a single, resili- 25 ent, loop extending between said member and surface structure.

4. In a building construction, a massive or basic building member serving as a support, metallic clips secured by nailing to a face only of said building member in spaced relationship, and a relatively light weight flat composite structure in spaced relationship to said member and serving as the finish face of the construction, said structure comprising a surfacing of set plastic material, 30 said clips being in engagement with an element of said structure and serving to maintain the spaced relationship between said member and said structure, said clips also permitting some structural movement between said member and 35 said structure whereby the set plastic surfacing will be kept substantially free from cracking. 40

5. In a building construction, a building member, a surface structure spaced away from said member and adapted to form the finish face of 45 said construction, and a plurality of individual clips secured to said building member and supporting said surface structure, each of said clips having a body portion formed of a single metallic strip provided with base means secured to the 50 face only of said member, and means on said clips spaced apart from said base for engaging a part of said surface structure, said clips being arranged to permit relative movement between said member and said surface structure without damage 55 to said structure.

6. In a building construction, a building member, a channel strip in spaced relation to said building member, clips securing said channel strip to said building member, said clips being 60 fastened to the face only of said member and in relatively slidable engagement with said channel strip, and a finish surface supported by said channel strip, said clips permitting relative movement between said member and said finish surface 65 after erection without damage to the surface.

7. In a clip for the purpose described, a substantially straight body part formed from a single strip of metal, means at one end of said body part forming a base for attaching said clip by 70 nails to the face only of a building member, and means on the other end of said body part for engaging another building member in spaced relation to said first building member.

8. In a clip for the purpose described, a body 75

part in the form of a resilient loop, means at one end of said body part forming a base for attaching said clip to the face only of a building member, and means on the other end of said body 5 part for engaging the edge of another building member in spaced relation to said first mentioned building member.

9. In a clip for the purpose described, a body part formed from a single strip of metal, means 10 at one end of said body part forming a base to be nailed to the face only of a building member, and means on the other end of said clip for engaging the edge of another building member in spaced relation to said first mentioned building 15 member, said base means being offset sufficiently relative to the remaining part of the clip to permit free perpendicular access to said base to permit driving a nail or the like through said base.

10. In a clip for the purpose described, a body part formed from a single metallic strip, means at 20 an end of said body part forming a base for attaching said clip to the face only of a building member, and means on another part of said clip for firmly engaging a flange of a channel strip 25 disposed in spaced relation to said building member.

11. In a clip for the purpose described, a body portion, means on one part of said body portion for engaging one structural member, and a base 30 flange formed on an end of said body portion and adapted to rest against the face only of another structural member, said flange being apertured to receive means for securing said flange against said last mentioned structural member 35 and being positioned in offset relationship to said engaging means whereby perpendicular access will be had to said apertured portion for inserting said securing means.

12. In a construction of the class described, a 40 supporting member, clip means having leg portions provided with lateral flanges attached to said member, said clip leg portions extending at an angle to said supporting member, a channel strip in spaced relation to said supporting member, and means on said clips for engaging the 45 flanges of said channel strip, each of said lateral flanges extending sufficiently to the side of the strip to permit ready access with a hammer in order to drive nails or the like through said 50 flanges into said member.

13. In a construction of the class described, a supporting member of somewhat irregular face surface, clip means having leg portions attached to said member, said leg portions being bendable 55 relative to other parts of the clips, and a furring strip supported by said clip means in spaced relation to said supporting member and in a substan-

tially uniform face plane regardless of the irregularities of said member face, said leg portions being disposed in angularly opposed relation one to the other and serving to compensate for variations in the spacing between said supporting 5 structure and said strip by an increased or decreased angularity of all or part of said leg portions.

14. In a construction of the class described, a supporting member having a somewhat variant 10 or uneven surface, a furring strip in spaced relation to said member but maintained in a substantially uniform face plane regardless of variations in said member face, and metallic clips connecting said furring strip to said member, said clips having leg portions bendable relative to other parts of the clips and extending at an angle outwardly from said furring strip to contact with said supporting member, the angle at which all or part of said clip legs extend away from said strip being 20 greatest where the strip and supporting member approach one another closest and least where the same are spaced more apart due to variations or unevennesses in the face of said member.

15. In a construction of the class described, a 25 supporting member, a plurality of clips secured to the face of said member, a furring strip supported by said clips in spaced relation to said member, said clips being arranged on opposite sides of said furring strip and comprising leg portions disposed in angularly opposed relation one to the other and at an inclination to the face of said supporting member.

16. A clip for the purpose described, comprising 30 a body portion, means on one part of said body portion for attachment to a supporting member, and means on another part of said body portion for attachment to a flat wall element to be supported in spaced relation to said supporting member, said clip having leg portions on said body 35 portion extending at an inclination to the face of said supporting member, said clip being relatively bendable intermediate said means whereby the spacing between said supporting members and wall element is variable by a simple bending 40 operation.

17. In a construction of the class described, a supporting member, an element in spaced relation to said member, and metallic clips connecting said element and member, said clips having a relatively bendable portion extending at an inclination to the face of said supporting member so that by bending said clips said member can be positioned in a substantially uniform plane regardless of unevennesses or variations in said supporting 50 member.

BRUNO E. BALDUF.
